UNITED STATES PATENT OFFICE.

HAROLD E. SLADE, OF GLEN RIDGE, NEW JERSEY, ASSIGNOR TO BEAVER MACHINE & TOOL CO. INC., OF NEWARK, NEW JERSEY, A CORPORATION OF NEW JERSEY.

HANDLE-CAP PLUG.

Application filed April 23, 1928. Serial No. 105,852.

My invention relates to a novel construction of a handle cap plug, wherein I employ a rigid, elongated handle of insulating material which is bored longitudinally to receive an electric cord, and constructed so as to have firmly mounted on one end thereof one member of an attachment plug, there being an outer ring surrounding the front end of the handle and said member of the attachment plug, said ring having a front and rear inwardly deflected lip or flange spun upon or otherwise firmly engaging respectively, the front end of said plug member and a shoulder on said elongated handle, so that said parts are rigidly clamped together or retained in juxtaposition, so that they are rotatable in unison as a unit, said plug member being fastened to the handle by other means, if desired.

By my novel construction I have produced an efficient handle cap plug, which is especially applicable for facilitating the insertion of attachment plugs into sockets, that are so arranged or positioned that they are not easily reached, as in the case of base board outlets or where the sockets are within long narrow globes or shades, which often surround an electric light socket or fixture. When a socket of this character is slightly out of reach, it is frequently quite difficult to plug into it, as for instance for connecting an iron, toaster, percolator, vacuum cleaner, and the like.

To the above ends, my invention consists of a novel construction of an elongated, hollow handle carrying an electric cord, and a member of an attachment plug secured thereto by a ring or shell having terminal front and rear inwardly deflected, annular lips or flanges, whereby said member of an attachment plug is readily and fixedly secured to said handle, the juxtaposed contracting walls of the handle and plug elements being flat or rectilinear.

To the above ends my invention consists of a novel construction of a device of the character described, which is neat and attractive in appearance, economical of construction, and which can be readily manually rotated at all points of use, my novel device being durable, reliable, simple, compact, convenient, efficient and satisfactory for use wherever it is found applicable.

For the purpose of illustrating my invention I have shown in the accompanying

drawings several forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Figure 1 represents a vertical sectional view of a handle cap plug, and its adjuncts embodying my invention, certain of the parts being shown in elevation, the shade and its adjuncts surrounding the socket member being shown dotted.

Figure 2 represents on a reduced scale a perspective view of a base board outlet, showing the manner of inserting my novel device thereinto.

Figure 3 represents a perspective view of the elongated handle and one member of an attachment plug disconnected therefrom.

Figure 4 represents a top plan view of the upper portion of Figure 3.

Figure 5 represents a side elevation of the upper portion of the handle member and one member of an attachment plug, the latter being shown in section.

Figure 6 represents a vertical sectional view of another embodiment of my invention, the section being taken on line 6-6 Fig. 7.

Figure 7 represents a top plan view of Figure 6.

Similar numerals of reference indicate corresponding parts.

1 designates my novel construction of handle cap plug, the same comprising an elongated handle 2 having a longitudinal passage or bore 3, through which passes the electric cord 4. The front end 4 of the handle is flat or rectilinear, or in other words extends at a right angle to the axis thereof, and is provided with a counterbore 5. The flat front end of the handle is formed with a flange 6, whereby the rear shoulder 7 is produced, which is engaged by the rear annular inturned flange 8 of the ring 9, the latter being provided with the forward or outer inwardly deflected flange 10 which engages the shoulder 11 of the plug member 12, which constitutes one member of an attachment plug. The member 12

is a flat bottomed, moulded member, having the flat wall or bottom 13, which rests upon the flat ended handle 2 when the parts are assembled, said member 12 having an opening 14 therethrough and being provided with the blades 15 which are of the usual construction and are provided with the oppositely located screws or binding posts 16 in which secure the terminals of the cord 4* in position, as will be understood from Figure 1. The blades 15 in the present instance have the offset feet 17 which are secured to the moulded member 12 by the screws 18, as seen in Figures 4 and 5. In practice the ring 9 has the lip 10 spun upon the shoulder 11, as seen in Figure 5, so that the member 12 and its adjuncts and the ring 9 can be handled as a unit. The lower edge of the ring 9, as seen in Figure 5, is extended sufficiently below the bottom wall 13 of the member 12, so that it completely encloses the front terminal flange 6 of the handle 2, after which the lower or rear peripheral edge of said ring 9 is spun upon the shoulder 7, thereby forming the flange 8; so that the finished article appears as seen in Figures 1 and 2. The blades 15 can be readily inserted into the socket member 19, (seen in Fig. 1), and the latter can readily be rotated into or out of position in the socket, the insertion of the blades 15 into the socket member 19 in the usual manner completing the electrical connection therewith.

20 designates a lamp shade shown in dotted lines, which is of the shape or size frequently surrounding the electrical socket or fixture 19, and is ordinarily quite difficult to plug into, but by my invention the socket member 19 is instantly and conveniently accessible, as is evident. In Figure 2, I have shown my invention as applicable to a base board outlet 21. It will be apparent that there will be no loosening of the ends of the cord 4* at their junction with the contact members, since the plug member 12 is firmly secured to the handle by reason of the in-turned flanges 8 and 10. The handle 2 further serves as a protection for the cord 4*, since it prevents the latter from contacting with the lower edges of the shade 20, which are frequently quite sharp.

I have shown the top of the member 12 as slightly counterbored to receive the ends of the cord 4*, but it will be apparent that this construction can be varied if desired, according to requirements.

While I have shown my invention as adapted to the attachment plug, of the more generally used type, one member of which comprises the disc 12 having the standard parallel blades or prongs 15, it will be apparent that my invention is equally adaptable to other types of plugs as the swivel type, wherein one member may be rotated on

pushed within the coacting attachment member.

In the construction seen in Figures 6 and 7, I have shown a different embodiment of the broad principle of my invention, where in a different construction of the cap member is shown secured or united to the elongated handle member by an equivalent means or fastening device.

In Figure 6 I have shown my novel device 22 as composed of the elongated handle member 23 having the bore or passage 24 therethrough, which is adapted for the reception of electric wires 4*, as seen in Figs. 1 and 2. The front end of the handle 23 is cup shaped or concaved, as indicated at 25 and receives the convex bottom portion of the moulded member 26, which is provided with the blades 27 and their adjuncts, all of substantially the same construction, as seen in Figures 4 and 5.

The shell or ring 28, which serves to unite the moulded or cap member 26, with the contiguous handle portion, has the front inwardly deflected lip or flange 29, which fixedly engages the front of the member 26, while the rear portion of said ring is spun or otherwise pressed or formed around the convex portion 30 of the handle 23, as indicated at 31, so as to form a unitary structure.

The cap member 26 is provided with the axial passage 32, so as to enable the electric wires to be readily connected to the binding posts of said cap member 26.

While the construction seen in Figures 6 and 7 may be a little more expensive to manufacture and assemble, than the construction seen in Figs. 1 to 5, it is a substantial equivalent thereof as will be apparent.

In all the embodiments of my invention, it will be apparent that the elongated handle and the moulded member, disc, or cap member can be readily assembled, and manipulated as a unit, and all the structures embody the broad principles and advantages pointed out with reference to Figures 1 to 5.

It will now be apparent that I have devised a novel and useful construction of handle cap plug which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. An attachment plug cap of an elongated type, comprising a disc-like member of insulating material, metal contact blades are attached thereto, an elongated handle-like member of insulating material having a shoulder and adapted to be attached to said disc-like member, and means for attaching the two members together comprising a metallic tubular member having front and rear inwardly deflected flanges engaging the front end of said disc-like member and the shoulder of the handle member to rigidly hold them together.
2. In a device of the character stated, a rigid elongated handle of insulating material having a front flat end and a front terminal flange forming a rear shoulder, said handle being bored longitudinally to receive an electric cord, a flat bottomed attachment plug member in contact with the front flat end of said handle, and a locking ring having a front inwardly deflected peripheral flange in fixed engagement with the front of
3. In a device of the character stated, a rigid elongated handle member having a terminal shoulder at an end thereof, said handle member being bored longitudinally to receive an electric cord, an attachment plug member at said end of said handle member having an opening therethrough in operative alignment with the bore of said handle member for receiving the end of an electric cord, and a metallic tubular member surrounding said end of said handle member and said plug member having a front terminal and inwardly extending peripheral flange in engagement with the front end of said plug member and having a rear terminal and inwardly extending peripheral flange in engagement with the shoulder of said handle member.

HAROLD E. SLADE.
